MACHINE COMPANY, OF PITTSBURG, PENNSYLVANIA.

STEAM-ENGINE VALVE.

SPECIFICATION forming part of Letters Patent No. 329,347, dated October 27, 1885.

Application filed August 15, 1885. Serial No. 174,476. (No model.)

To all whom it may concern:

Be it known that we, H. HERMAN WESTINGHOUSE, residing at New York, in the county and State of New York, and WILLIAM A. BOLE, residing at Pittsburg, in the county of Allegheny and State of Pennsylvania, both citizens of the United States, have jointly invented or discovered certain new and useful Improvements in Steam-Engine Valves, of which improvements the following is a specification.

In the accompanying drawings, which make part of this specification, Figure 1 is a vertical central section through a steam-engine distribution-valve and its chest or chamber, illustrating the application of our invention; and Fig. 2, a transverse section through the same at the line *xx* of Fig. 1.

Our invention relates to steam-engine distribution-valves of the piston type, and is more particularly designed for application to single-acting engines of the class in which a pair of cylinders is located above a closed crank-case, the functions of steam admission, exhaust, and cut-off being performed by a distribution-valve common to both cylinders, an instance of which is exemplified in Reissued Letters Patent No. 10,603, granted and issued to The Westinghouse Machine Company, as assignee of H. H. Westinghouse, May 26, 1885.

The object of our invention is to perfect the balancing of a valve of such character by the equalization of pressure thereon, and to relieve the valve-chest from leakage and water of condensation.

To this end our invention, generally stated, consists in the combination, with a tubular valve having an open-ended piston at each of its ends, of a guide-piston and a supplemental back-pressure piston corresponding in area and working, respectively, in opposite ends of the valve-casing; also, in the combination of a valve as described, a valve chest or chamber, and a relief-passage leading from the upper end of the valve-chamber to a suitable point of discharge.

The improvements claimed are hereinafter fully set forth.

The distribution-valve 12, herein selected for illustration, is, as in Reissued Letters Pat-

ent No. 10,603, before referred to, composed 50 of an upper piston, 38, and a lower piston, 39, connected by a hollow or tubular body portion, and secured upon a valve-stem, 16, to the lower end of which is connected a guide-piston, 17, working in an open-ended guide-cylinder, 18, projecting downwardly from a transverse partition in the valve-chamber 3, above a closed crank-case, 2. The valve is reciprocated by an eccentric-rod, 19, coupled to a pin fixed to the guide-piston 17, and works 60 in a sleeve or bushing, 40, in the valve-chamber 3. Steam is supplied to the valve-chamber and to the space between the main pistons 38 39 of the valve through a steam-supply nozzle, 11, and, by the movements of the 65 valve, is alternately admitted to and exhausted from two single-acting cylinders, 11, located on opposite sides of the valve-chamber, through ports 13 and 14, respectively, the exhaust being effected through the center of the valve, 70 and from the space below its lower piston, 39, into an exhaust passage or nozzle, 15, to which the exhaust-pipe is connected. The upper end of the casing of the valve is closed by a tight head or bonnet, 64, and the lower by the 75 guide-piston 17; and it will be seen that the valve is subject to steam-pressure between its pistons 38 39, (which pressure is balanced, as said pistons are of equal areas,) and to the back-pressure of the exhaust upon its inner 80 surface and upon the area of the guide-piston 17. Under the construction employed prior to our invention, as shown in Reissue 10,603, such pressure upon the piston 17 was unbalanced, the valve being open at its upper end 85 to the space closed by the head 64. To obviate this objection, and thereby effect an equalization of exhaust-pressure upon the valve, a supplemental back-pressure piston, 62, corresponding in area with the guide-piston 17, is 90 secured upon the valve-stem 16, adjacent to the upper valve-piston, 38, said piston fitting truly and working with the valve and valve-stem in the bushing 40 of the valve-chamber. Equal pressure in opposite directions being 95 thus exerted by the exhaust upon the pistons 17 and 62, the valve will be perfectly balanced as against back-pressure, the advantage of

which is specially important in automatic cut-off engines in relieving the governor and movable eccentric from the disturbing action which would otherwise tend to be exerted 5 upon them twice in each revolution of the engine by unbalanced back-pressure upon the guide-piston of the valve.

In order to carry off any exhaust-steam leakage or water of condensation that may 10 gain access to the space between the supplemental piston 62 and the head 64 of the valve-chamber, as well as to prevent resistance to the movement of the valve by compression in said space, a relief-passage, 63, is formed in 15 the wall of the valve-chamber 3, said passage opening into the chamber above the level of the piston 62, when at the upper extremity of its traverse, and leading therefrom to the crank-case 2, or to any other suitable and convenient point of discharge. In the instance 20 shown the upper portion of the passage 63 is formed by drilling at right angles into the casting, the outer ends of the holes being closed by proper plugs, and the lower portion 25 consists of a pipe which may be either set in the mold and the metal of the valve-chamber cast partially around it, or may be connected to the valve-chamber after the upper portion of the passage has been formed therein.

30 We claim herein as our invention—

1. The combination of a steam-engine valve having two end pistons connected by a tubular body, a guide-piston and a supplemental

back-pressure piston corresponding, substantially, in area and secured upon opposite ends 35 of the stem of the valve, a valve-chamber having a closed head at one end and an open-ended guide-cylinder at the other and ports governed by the end pistons of the valve, a steam-passage opening into the valve-chamber 40 between the end pistons of the valve, and an exhaust-passage leading out of the valve-chamber between an end piston of the valve and the guide-piston, substantially as set forth.

2. The combination of a steam-engine valve 45 having two end pistons connected by a tubular body, a guide-piston and a supplemental back-pressure piston corresponding, substantially, in area and secured upon opposite ends 50 of the stem of the valve, a valve-chamber, substantially as described, and a relief-passage leading from the space between the supplemental back-pressure piston and the head of the valve-chamber to a suitable point of discharge, substantially as set forth. 55

In testimony whereof we have hereunto set our hands,

H. H. WESTINGHOUSE.
WILLIAM A. BOLE.
